UNITED STATES PATENT OFFICE.

CORA B. WEBSTER, OF HAVERHILL, MASSACHUSETTS, ADMINISTRATRIX OF HAROLD A. WEBSTER, DECEASED, ASSIGNOR TO SINGLE THREAD LOCK STITCH COMPANY, OF HAVERHILL, MASSACHUSETTS, A CORPORATION OF MAINE.

SHOE-STITCHING MACHINE.

No. 914,091.

Specification of Letters Patent.

Patented March 2, 1908.

Application filed January 18, 1906. Serial No. 295,833.

To all whom it may concern:

Be it known that HAROLD A. WEBSTER, deceased, late a citizen of the United States, and a resident of Haverhill, in the county of 5 Essex and State of Massachusetts, did invent certain new and useful Improvements in Shoe-Stitching Machines, of which the following is a specification.

In the shoe-stitching machines now commonly used the construction is such that the needle bar is caused to dwell for an appreciable interval at the upper limit of its stroke, this being due in some machines to the mode of operation of the means for varying 10 the extent of upward movement of the needle bar to correspond with different thicknesses of material operated upon, and inasmuch as the thread is held under tension by the needle while the latter is at the upper 15 limit of its movement, this tension on the thread has necessarily been maintained for a fractional part of each stroke, during which the shoe being operated upon is caused to undergo certain movements such as feeding 20 movements and changes in the direction of the same. The result has been not only that the freedom of these movements has been restricted by the connection of the shoe with the needle through the loop held by 25 the latter under tension, but also that the tendency of the thread to break has been greatly increased, such breakage having been found very troublesome in many cases. This invention is intended to overcome the 30 liability to breakage of the thread in this manner, and also to increase the ease and freedom of movement of the shoe being stitched, and to this end means are provided which, without interfering with the variability 35 of the stroke of the needle, operate to cause the latter to move downward for a certain distance immediately after reaching the upper limit of its stroke, regardless of its actual position when this limit is reached, 40 the result being that the tension put upon the looped thread by the upward movement of the needle is immediately released by a downward movement of the needle and the consequent slackening of the loop as soon 45 as the needle bar has completed its upward movement.

This invention may have various embodi-

ments according to the type or specific construction of the stitching machine with which it is combined or in connection with 55 which it is used, but for convenience it is herein shown and described as combined in the form of an attachment with a shoe-stitching machine which is otherwise constructed substantially as shown in Patent 60 No. 710,612, granted October 7, 1902 on the application of E. P. Richardson, for a shoe sewing machine, and the illustration in the accompanying drawings corresponds in the use of reference numerals and otherwise with 65 the drawings of said Richardson patent, which are here reproduced to a sufficient extent to illustrate the construction and mode of operation of the parts necessary for an understanding of the present improvement. 70

In these drawings, Figure 1 is a perspective view of the front end of the head of the machine, with parts broken away. Fig. 2 is a transverse section through the same. Fig. 3 is a perspective view of a detail hereinafter described; and Fig. 4 is a sectional view illustrating another detail. 75

Referring to the drawings, 3 indicates the base plate of the head of the machine and 6 indicates an upright secured thereto, in 80 which upright is journaled the front end of the needle-driving shaft 8, said shaft projecting rearwardly therefrom to a point where it receives suitable rotating means which it is not necessary to illustrate. 85

60 represents the presser foot, which in this machine is automatically adjusted according to the thickness of the work, said presser foot being adjustably secured to a finger 62 projecting downwardly and laterally from the lower end of a bar 61. Said bar 61 is mounted to slide vertically on suitable guides, the guide at the upper end of the bar consisting of a vertical slot 65 formed in said bar and a screw pin 66 passing through 90 the same into a bracket 67 which is bolted to the top of the upright 6. At its lower end said bar 61 is guided by a flanged plate 68 secured to the side of the base plate 3. Near the base plate the bar 61 is formed with a 95 shoulder 70 and to the side of the bar above said shoulder is secured a clip 71 having a shoulder confronting that at 70. Between these shoulders is provided a space for the

reception of a pin 72 which projects forwardly from an arm 73 rigidly secured to a shaft 74, said shaft being journaled in bearings afforded by the uprights carried by the 5 head of the machine.

The stitching needle is shown at 105 and is clamped in the lower end of a needle bar 106 by a clamp 107, said bar 106 being arranged to reciprocate vertically in guides carried respectively by the bracket 67 and the base plate 3. On the forward end of the shaft 8 is mounted a crank pin 109 which is connected by a link 110 with a lever 111, the latter being fulcrumed on a collar 112 rigidly secured to the needle bar, this pivotal connection of said lever to the collar 112 permitting a certain amount of free play or lost motion between the crank pin and the needle bar. The collar 112 is provided with two lugs 113 and 114 so positioned that when the link 110 descends, the lever 111 swings downward freely until it encounters the lug 113 without effecting any downward movement of the needle bar. The continued movement of this link, however, after the lever 111 strikes the lug 113, causes the needle bar to move downward, which downward movement always stops at exactly the same point.

30. For determining the upward movement of the needle bar there is provided a lever 116 fulcrumed upon a fixed stud 115 and having its end 117 extending forward into the path of the free end of the lever 111. Said lever 116 is fulcrumed between its ends, and its shorter arm 118 projects downward and rests against a stop bar 119 adjustably secured by screws 120, 121 to the arm 73, a spring 122 being attached to said arm 118 and to the upright 6 so that said arm is always held against the end of the stop bar 119. The position of the arm 73 is varied automatically according to the thickness of the work upon which the presser foot rests, and hence the lever 116 is correspondingly adjusted about its fulcrum, so that the end 117 thereof is adapted to serve as a variable fulcrum for the lever 111 on the upstroke of the needle bar. The initial upward movement of the needle bar may be caused by the engagement of the lever 111 with the lug 114, but as soon as the end of said lever comes in contact with the part 117 the fulcrum point is immediately changed and the needle bar moves still farther upward with a rapid movement, the limit of this upward movement varying inversely with the height of the fulcrum 117 from the base plate 3. The result of this arrangement is that the movement of the needle bar is not continuous, in that said bar dwells for a certain interval at each end of its stroke, the position reached by this needle bar at the upper limit of its stroke being also variable. A piece of 65 friction material 600 is inserted between the

upper portion of the needle bar and the arm 67 for the purpose of offering a sufficient resistance to the movement of said bar to hold it stationary at the limit of its upward movement, the pressure of this friction material on the bar being variable by means of an adjusting screw pin 1601.

123 is the cast off, which is secured upon the end of a narrow bar 124 mounted to slide in a groove in the needle bar 106. At 75 its upper end said bar projects from said groove at 125 and is connected by a spring 126 with the collar 112. Another collar 127 surrounds the needle bar between the projecting end 125 and the top of the collar 112, 80 which collar 127 is provided with an upwardly-extending arm 128 passing between the bracket 67 and a piece of friction material 129, held against said arm by a clip 130. The needle bar also carries a stud or clip 131 85 located a short distance above the collar 112, so that the cast-off has a certain amount of lost motion at each reciprocation of the needle bar, said clip 131 serving as a stop to engage the collar 127 and force the same positively downward after a limited relative downward movement of the needle bar has occurred.

The feeding mechanism comprises a point 131 secured to an arm 134, which arm is 95 pivotally secured to the lower end of a bar 133, the illustration of the connections between this feeding mechanism and the other parts and the means for operating the same being immaterial to the present invention.

The construction and operation of the parts above described are the same as shown and described in the Richardson patent previously referred to, and it will be seen that as thus constructed the needle bar will be caused to dwell for a certain interval after it reaches the limit of its upward movement by reason of the free play allowed to the lever 111 between one or the other of the upper fulcrums or stops 114 and 117, as the case 110 may be, and the lower stop 113, which dwell will vary according to the adjustment of the stop bar 119 on the lever 73 and also according to the thickness of the work. According to the present invention means are provided for preventing this dwell by causing the needle bar to move downward immediately after reaching said upper limit of its movement as fast as such downward movement is permitted by the parts already described for operating said bar, and in the present instance the invention is illustrated as embodied in an attachment adapted to be applied or added to the parts already described, which attachment comprises a bracket *a* 115 adapted to be bolted to the top of the bracket 67, and a spring-pressed member *b* mounted in said bracket *a* to move vertically in such a position that when the needle bar 120 approaches the limit of its upward move- 130

ment, it will engage said member *b* and lift the same against the pressure of its actuating spring, so that, as soon as the needle bar is free to move downward, it will be caused to do so by said spring. According to the construction herein represented, said spring-pressed member *b* consists of a plunger mounted to slide vertically near its lower end in an arm *c* extending horizontally from the bracket *a*, directly above the needle bar, and also mounted at its upper portion to slide in a sleeve *d* passing vertically through another horizontal arm *e* extending from said bracket *a*, and externally screw threaded and provided with a head *f* so as to be capable of vertical adjustment in said bracket. A collar *g* is rigidly secured to the plunger *b* above the arm *C* and serves as a stop to limit the downward movement of said plunger, and above said collar a spiral spring *h* surrounds the plunger and bears at its ends upon said collar and upon the lower end of the sleeve *d*, which spring is adjusted by means of said sleeve to give a sufficient downward pressure to overcome the frictional resistance afforded by the friction device 600. As thus constructed, when the needle bar moves upward it eventually comes in contact with the lower end of the plunger *b* and lifts the latter with it during the remainder of its upward movement, at the end of which movement said plunger immediately operates to force the needle bar downward until the stop collar *g* comes in contact with the arm *c*, thus immediately slackening the loop held by the needle and relieving the tension on the thread as previously explained.

It will be observed that the means for forcing the needle bar downward immediately after it reaches the limit of its upward movement act independently of the means for raising the needle bar through a variable distance and for forcing it through the work being operated upon, that is to say, the construction is such that the adjustment or variation of the upward stroke of the needle bar is not interfered with; and it is to be understood that while it is convenient and desirable in most cases to embody the present improvements in the form of an attachment which can be applied to existing machines, yet such an arrangement is not essential, since the invention may be variously constructed and modified and may be embodied in the structure of the stitching machine itself, whether of the type herein represented or of other types such as are well known in the art.

What is claimed is:

1. In a stitching machine, the combination of a needle bar and reciprocating means therefor, means for varying the upward stroke of said bar, and means supplemental to said reciprocating means for moving said

bar downward immediately after it reaches the limit of its upward movement.

2. In a stitching machine, the combination of a needle bar and reciprocating means therefor, means for varying the upward stroke of said bar, and a spring-pressed member operating independently of said reciprocating means to force the needle bar downward immediately after it reaches the limit of its upward movement. 70

3. In a stitching machine, the combination of a needle bar and means for operating the same, said means permitting a dwell of said bar at the limit of its upward movement, and means supplemental to said operating means for causing a downward movement of the needle bar immediately after it reaches said limit. 75

4. In a stitching machine, the combination of a needle bar and means for operating the same, said means having a free downward movement after said bar has reached the limit of its upward movement, and means for causing said needle bar to follow said operating means downward during the 80 free movement of the latter. 85

5. In a stitching machine, the combination of a needle bar and means for operating the same, said means permitting said bar to dwell at the limit of its upward movement, 95 and a spring-pressed member located in the path of the upward movement of said bar and operating to engage said bar and force the same downward after it reaches said limit of upward movement. 100

6. In a stitching machine, the combination of a needle bar and reciprocating devices therefor, a presser foot mechanism, and means controlled thereby for effecting the variable upward movement of said bar, said 105 means permitting a dwell of the bar at the limit of its upward movement, and supplementary means for forcing said bar downward immediately after it reaches said limit.

7. An attachment for stitching machines, comprising a bracket, a vertically-movable member carried thereby and adapted to be located in the path of upward movement of a needle bar, and means for exerting a downward pressure on said vertically-movable 115 member. 110

8. An attachment for stitching machines, comprising a bracket, a plunger mounted to slide vertically therein and adapted to be located in the path of upward movement of the needle bar, and a spring constantly tending to force said plunger downward. 120

9. An attachment for stitching machines, comprising a bracket, a plunger mounted to slide vertically therein and adapted to be located in the path of upward movement of the needle bar, a spring constantly tending to force said plunger downward, and means for varying the pressure exerted by said spring. 125

10. An attachment for stitching machines, comprising a bracket adapted to be secured to the head of a stitching machine, and provided with arms extending horizontally over 5 the needle bar, a threaded sleeve mounted in one of said arms and vertically adjustable therein, a plunger mounted to slide vertically in the other horizontal arm and in said sleeve, a stop collar carried by said plunger, 10 and a spring located between said stop collar and adjustable sleeve, and acting to apply a

downward pressure to said plunger, substantially as described.

Signed at Haverhill, Massachusetts, this twenty-sixth day of December, 1905.
